UNITED STATES PATENT OFFICE.

MICHAEL HOFFMANN, OF IVANHOE, MINNESOTA, ASSIGNOR OF ONE-HALF TO F. R. KLUCZNY, OF IVANHOE, MINNESOTA.

SPARK-PLUG.

1,344,892.

Specification of Letters Patent. Patented June 29, 1920.

Application filed May 16, 1919. Serial No. 297,569.

To all whom it may concern:

Be it known that I, MICHAEL HOFFMANN, a citizen of the United States, residing at Ivanhoe, in the county of Lincoln and State of Minnesota, have invented certain new and useful Improvements in Spark-Plugs, of which the following is a specification.

The invention relates to spark plugs for use in connection with the ignition system of an internal combustion engine, the purpose being to provide a spark plug which is free from the usual insulating core of porcelain or similar material which is susceptible to breakage by heat or rough usage. Moreover, the invention aims to provide a spark plug which is not liable to be easily fouled by carbon, oil or other matter and which therefore does not require frequent cleaning.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the accompanying drawing, Figure 1 is a view in elevation of a spark plug embodying the invention.

Fig. 2 is a vertical central section of the plug showing the parts on a larger scale.

Fig. 3 is a top view of the plug.

Fig. 4 is a view of the plug inverted and as seen from the lower end.

Corresponding and like parts are referred to in the following description and indicated in the several views of the drawing by like reference characters.

The body of the plug consists of a shell 1, the upper portion of which is of polygonal form for reception of a wrench or other tool and the lower portion of which is externally threaded for engagement with the cylinder or head of an internal combustion engine. The upper portion of the shell 1 is enlarged and internally screw-threaded to receive a gland or nut 2. The center electrode 3 passes through the shell 1 and its upper end is threaded to receive the usual binding nut 4 and its lower end is formed with a shoulder 5, whereby to

limit the upward movement of the electrode and enable the same to be cranked to the shell.

Insulation is provided at the ends and intermediate the plug. The upper insulation 6 preferably consists of fiber, such as compressed paper, although any suitable insulating material may be employed. The lower insulation 7 consists of mica, which is provided in a number of layers or disks and which is confined between the shoulder 5 and the lower end of the shell 1. The intermediate insulation consists of a plug 8 of asbestos, or like fibrous material compressed into a solid mass. A number of layers of mica 9 are disposed below the plug 8 and are supported upon the inner shoulder formed at the lower end of the upper enlarged portion of the shell. A packing ring 10 of metal, such as copper receives the plug 8 and sustains the end thrust of the gland or nut 2 when the latter is screwed into the shell 1 to compress the intermediate insulation consisting of the plug 8 and mica 9. The several insulating elements are centrally apertured to provide for the passage of the electrode 3 which latter is retained in place against endwise displacement by the shoulder 5 and the lower binding nut 4.

It will be observed that the lower end of the shell is completely closed by the mica 7, thereby preventing any oil or gases from entering the lower portion of the shell and fouling the same. It is also observed that the mica 7 is susceptible of resisting a high temperature and the plug being free from insulation of a nature such as porcelain is not liable to be rendered unfit for service by having the insulation fractured by heat or handling. Moreover, it is not necessary to take the plug apart for purposes of cleaning because there is not liability for carbon or oil to reach the interior of the plug which is sealed by the end insulating elements 6 and 7.

The foregoing description and the drawing have reference to what may be considered the preferred, or approved form of my invention. It is to be understood that I may make such changes in construction and arrangement and combination of parts,

materials, dimensions, et cetera, as may prove expedient and fall within the scope of the appended claims.

Having thus fully described my invention, what I claim as new and desire to secure by Letters Patent is:—

1. A spark plug, comprising a shell, an insulating element within the shell, a gland threaded to the shell and confining the insulating element therein, insulating elements closing the outer end of the shell and gland, an electrode passing through the gland, shell and the inner and outer insulating elements, means applied to opposite 15 end portions of the electrode for securing the end insulating elements, and an electrode at the inner end of the shell coöperating with the inner end of the electrode passing through the shell and gland to form 20 the spark gap wholly beyond the insulating element at the inner end of the shell.

2. A spark plug, comprising a shell, mica closing the lower end of the shell, pliable insulation closing the upper end of the shell, insulating material within the shell including mica and a plug of fibrous material, a gland threaded into the shell for confining the intermediate insulation, an electrode passing through the several insulating elements and provided at its lower end with a 30 shoulder and having its upper end threaded for a short distance and binding nuts mounted upon the threaded end of the electrode for retaining it and the upper and lower insulating elements in position. 35

In testimony whereof I affix my signature in presence of two witnesses.

MICHAEL HOFFMANN.
